CARDING ENGINE

Robert B. Jenkins and Glenn R. Hooper,
Gastonia, N. C.

Application November 7, 1938, Serial No. 239,364

5 Claims. (Cl. 19—107)

This invention relates to carding engines, and the primary object is to provide simple and efficient means for screening the waste from the licker-in roll, whereby the fly or lint which forms part of said waste and is valuable enough to save and use is separated from the motes which constitute the remainder of said waste and has little or no value.

With the above general object in view, and others that will become apparent as the nature of the invention is better understood, the present invention consists in the novel form, combination and arrangement of parts hereinafter more fully described, shown in the accompanying drawings and claimed.

In the drawings:

Figure 1 is a fragmentary longitudinal sectional view of a carding engine equipped with a waste screening and separating device constructed in accordance with the present invention.

Figure 2 is an enlarged elevational view, partly broken away, of the screening and separating device per se, and as seen looking toward the right of Figure 1; and

Figure 3 is a fragmentary vertical section on line 3—3 of Figure 2.

Referring in detail to the drawings, the carding engine includes the usual frame 5 having suitable bearings for the main carding cylinder 6 and licker-in roll 7. The usual grid-like screen 8 is disposed beneath the licker-in roll 7, and the frame 5 has the usual door or closure 9 at the feed end of the engine.

The waste from the licker-in roll 7 drops through the screen 8 into the bottom of the frame, as does also the waste from the main carding cylinder 6. The waste from the main carding cylinder 6 is valuable and composed entirely of fly or lint, but the waste from the licker-in roll 7 includes valuable fly or lint, and motes which are of little or no value.

In accordance with the present invention, means is provided for screening the waste from the licker-in roll 7 so as to separate the motes from the fly or lint, the fly or lint of the licker-in roll waste being directed into that portion of the frame which receives the waste from the main carding cylinder, and the motes being collected at a different point within the frame and maintained separate from the fly or lint from the main carding cylinder and separated from the waste of the licker-in roll. In this way, the motes are maintained separate from the fly or lint so that one may be removed independently

of the other, and the fly or lint forming part of the waste from the licker-in roll is recovered.

In carrying out the present invention, brackets 10 are secured to opposite sides of the frame 5 of the engine, the lower attaching portions of said brackets having longitudinal slots as at 11 to permit adjustment of the brackets forwardly or rearwardly for a purpose which will presently become apparent. The present screening and separating device includes an upper section 12 rigidly secured to the upper portions of the brackets 10 as at 13, and a lower section 14 hinged at 15 to the upper section 12 for vertical swinging movement. The lower section 14 is limited in its downward and forward swinging movement 16 to a substantially vertical position by abutting the brackets 10, and it will be noted that the sections 12 and 14 simply form a transverse partition preferably made of sheet metal. In this way, the space within the frame 5 is divided into front and rear compartments adapted to respectively receive the motes and the fly or lint, as will also presently become apparent. The fly or lint accumulates at the right hand side of the partition 12, 14 as viewed in Figure 1, and the motes accumulate at the left hand side thereof. Obviously, upon opening the door 9, the motes may be removed from the left hand compartment, after which the lower section 14 may be swung upwardly to permit access to the fly or lint accumulated at the right hand side of partition 12, 14, for removal separately. To facilitate swinging the section 14 rearwardly and upwardly, the same may be provided at the bottom with a suitable handle 15, and any suitable means may be provided for temporarily holding the section 14 in its open position.

The upper section 12 is provided at the top with a forwardly and downwardly inclined grid-like screen 16 which may be formed by bending the upper portion of section 12 at an angle and then slotting this portion as at 17 to provide uniformly spaced grid bars 18 therebetween extending transversely of the machine when the device is in use. The bars may be reinforced as at 19 so as to be of hollow triangular form in cross section as shown clearly in Figure 3. The arrangement is such that the screen 16 is positioned to extend forwardly and downwardly beneath the licker-in screen 8 immediately in front of the mote knives K. By adjusting the brackets 10 as permitted by their slots 11, the device may be adjusted forwardly or rearwardly with respect to the licker-in roll so as to get the best effect in separating the motes from the fly of 55

the waste from the licker-in roll. This waste passes through the licker-in screen 8 and falls upon the screen 16. Due to the inclined position of the latter, the light weight fly or lint of the waste will pass forwardly and downwardly so as to fall into the bottom of frame 5 at the right hand side of the partition 12, 14 where the waste from the main carding cylinder 6 accumulates. At the same time, the heavier motes pass through the screen 16 and fall into the bottom of frame 5 at the left hand side of the partition 12, 14. In this way, the motes are separated from the fly or lint with respect to the waste from the licker-in roll, and such motes are maintained separate from the fly or lint. Also, the fly or lint forming part of the waste from the licker-in roll is accumulated with the fly or lint constituting the waste from the main carding cylinder. As above described, the motes may be first removed and then the fly or lint may be removed separately. I am aware of the fact that it has been previously proposed to maintain the waste from the licker-in roll separate from the waste from the main carding cylinder, but in no prior instance has efficient provision been made for screening the waste from the licker-in roll so as to separate the motes from the fly thereof and so as to cause the fly of this waste to accumulate with the waste from the main carding cylinder, the motes being maintained separate from the fly for separate removal from the machine.

It will be apparent that the device is extremely simple and durable in construction, efficient in operation, readily manufactured and installed, and economical to manufacture.

What we claim as new is:

1. In combination with the main frame, the licker-in roll, and the main carding cylinder of a carding engine, means mounted within said frame to receive the waste from said licker-in roll and separate the motes from the fly thereof and to maintain said motes separate from said fly as well as to deliver the latter for accumulation with the waste from the main carding cylinder, said means including a transverse partition having a fixed upper section and a lower section hinged to said upper section for vertical swinging movement so as to permit access to and removal of the fly accumulated within the frame after removal of the motes, and means to effect adjustment of said partition longitudinally of the frame including mounting brackets for the partition adjustable longitudinally of the frame for varying the position of the partition with respect to the licker-in roll.

2. In combination with the main frame, the licker-in roll, and the main carding cylinder of a carding engine, means mounted within said frame to receive the waste from said licker-in roll and separate the motes from the fly thereof and to maintain said motes separate from said fly as well as to deliver the latter for accumu-

lation with the waste from the main carding cylinder, said means including a transverse partition having a fixed upper section and a lower section hinged to said upper section for vertical swinging movement so as to permit access to and removal of the fly accumulated within the frame after removal of the motes, and means to effect adjustment of said partition longitudinally of the frame including mounting brackets for the partition adjustable longitudinally of the frame for varying the position of the partition with respect to the licker-in roll, said brackets affording abutments for limiting swinging movement of the lower partition section in one direction to a vertical position.

3. In combination with the main frame, the licker-in roll, and the main carding cylinder of a carding engine, means mounted within said frame to receive the waste from said licker-in roll and separate the motes from the fly thereof and to maintain said motes separate from said fly as well as to deliver the latter for accumulation with the waste from the main carding cylinder, said means including a transverse partition having a fixed upper section and a lower section hinged to said upper section for vertical swinging movement so as to permit access to and removal of the fly accumulated within the frame after removal of the motes, and an inclined separating screen carried by the top of said fixed upper section of the partition.

4. In combination with the main frame, the licker-in roll, and the main carding cylinder of a carding engine, an inclined screen arranged beneath said licker-in roll to receive the waste from the latter and separate the motes from the fly thereof, a transverse partition mounted within said frame coincident with the lower edge of said screen, said partition including a fixed upper section and a lower section hinged to said fixed upper section for vertical swinging movement, and means to limit swinging movement of said lower section in one direction to a vertical position.

5. In combination with the main frame, the licker-in roll, and the main carding cylinder of a carding engine, an inclined screen arranged beneath said licker-in roll to receive the waste from the latter and separate the motes from the fly thereof, a transverse partition mounted within said frame coincident with the lower edge of said screen, said partition including a fixed upper section and a lower section hinged to said fixed upper section for vertical swinging movement, means to limit swinging movement of said lower section in one direction to a vertical position, said screen being rigid with said upper partition section so that the screen and the partition form a unitary structure, and means to adjust said unitary structure longitudinally of the frame.
